COMPUTER OPERATOR'S CONSOLE

Walter F. Kraus and Walter S. McCormick, Jr., Pough-
keepsie, N.Y., assignors to International Business
Machines Corporation, New York, N.Y., a corporation
of New York

Filed Feb. 28, 1964, Ser. No. 78,828

Term of patent 14 years

(Cl. D26—5)

FIG. 1

FIG. 2

FIG. 1 is a view in perspective of the front and left-hand side of a computer operator's console showing our new design, and

FIG. 2 is a view in perspective of the rear and right-hand side of FIG. 1.

We claim:

The ornamental design for a computer operator's console, substantially as shown.
